(57) **CLAIM**

The ornamental design for a pull-out spout, as shown and described.

DESCRIPTION

FIG. 1 is a front perspective view of the pull-out spout showing my new design;

FIG. 2 is a rear perspective view thereof;

FIG. 3 is a right side elevational view thereof;

FIG. 4 is a left side elevational view thereof;

FIG. 5 is a top plan view thereof;

FIG. 6 is a front elevational view thereof;

FIG. 7 is a rear elevational view thereof; and,

FIG. 8 is a bottom plan view thereof.

The broken line showing of the on-off button in FIGS. 1-5 and 7, and of the faceplate with spray apertures in FIG. 8, are for purposes of illustration only and form no part of the claimed design.
